UNITED STATES PATENT OFFICE.

JOHN WILLIAM MUMFORD, OF PHILADELPHIA, PENNSYLVANIA.

DESIGN FOR A RUG AND CARPET HOLDER.

57,370.

Specification for Design.

Patented Mar. 15, 1921.

Application filed July 22, 1920. Serial No. 398,322. Term of patent 14 years.

To all whom it may concern:

Be it known that I, JOHN WILLIAM MUMFORD, a citizen of the United States, residing in the city and county of Philadelphia, State of Pennsylvania, have invented a new, original, and ornamental Design for Rug and Carpet Holders, of which the following is a specification, reference being had to the accompanying drawing, forming part thereof.

The figure is a perspective view of a rug and carpet holder, showing my new design.

I claim:—

The ornamental design for a rug and carpet holder, as shown.

JOHN WILLIAM MUMFORD.
